(57) **CLAIM**

The ornamental design for an electrical device, as shown and described.

DESCRIPTION

FIG. 1 is a front perspective view of an electrical device illustrating my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

Uniformly-sized broken lines illustrate features that form no part of the claimed design. Long-short broken lines illustrate a boundary that forms no part of the claimed design.
